TEXTILE EQUIPMENT

Charles Braglio, Arnold, Pa., assignor to Aluminum Company of America, Pittsburgh, Pa., a corporation of Pennsylvania

Application February 21, 1940, Serial No. 320,045

5 Claims. (Cl. 242—123)

This invention relates to improvements in metallic bobbins, spools, and the like such as are employed in the textile industry.

The textile industry is employing an ever-increasing use of metal equipment to replace equipment constructed from wood, ceramics, and various synthetic plastics. The light metals and their alloys, such as magnesium, aluminum, and alloys thereof, find ready adaptability in the textile industry for this purpose in view of their inherent weight-saving property as well as their resistance to mechanical wear and chemical corrosion.

For the most part, metallic textile equipment now in use, such as spools, bobbins, pirns, and the like, have been constructed from sheet metal that has been formed to shape, seamed or welded, and thereafter provided with flanges attached to the formed sheet metal body by screws or other fastening members. Such equipment is insufficiently sturdy in its construction to withstand the abuse arising out of the high speeds of operation of textile equipment employing these instrumentalities, the increase in speeds being a direct result of the weight-saving factor derived from the use of light metals and their alloys. Further, it is inherently difficult to dynamically balance such equipment, particularly at high operating speeds, in view of the seams, joints and welds, which introduce unsymmetrical or eccentric loading conditions.

It is an object of this invention to provide a textile bobbin of sturdy construction which will have all the advantages of light weight construction, will retain its dynamic balance over long periods of service, and will at the same time be economical in its production.

It is a further object of this invention to provide a spool or the like having a minimum number of parts and which may be produced from commercially fabricated stock.

Further objects and advantages of the invention hereinafter described in more detail will be manifest from a consideration of the specification when taken in the light of the drawing appended hereto, in which:

Fig. 1 represents an elevational view, partially in section, of the body or barrel portion of a preferred spool;

Fig. 2 represents an end view of the body or barrel illustrated in Fig. 1;

Fig. 3 represents a fragmentary sectional view of a spool having a flange disposed at its end;

Figs. 4 and 5 represent fragmentary sectional views illustrating two modes of construction for 55

securing a flange to the body or barrel of the spool, bobbin, or pirn of this invention; and

Fig. 6 represents a fragmentary end view of the flanged spool of this invention.

Referring to the drawing, the body or barrel of the spool of this invention is made from a standard commodity preferably in the form of cylindrical tubing 10 having internal ribs 11 formed integral with the wall of said tube. As will be evidenced from an inspection of Figs. 1 and 2, the ribs 11 are preferably circular in cross-section and are connected to the inner surface of the tubing 10 by means of a relatively short connecting web 12. This form of internally ribbed tubing readily lends itself to fabrication by an extrusion process which permits the fabrication of relatively thin-wall tubing having integral internal ribs 11 connected to the relatively thin wall through the medium of the short connecting webs 12.

The internally ribbed tubing 10 may be produced in any desirable length by an extrusion process as a stock commodity, and in the construction of the spool of this invention sections of tubing are cut to the desired length of spool required. To prepare a section of tubing for subsequent fabrication of a flanged spool, the wall 14 is removed, as by a cutting or lathe-turning operation, to expose extending portions 20 of the aforementioned ribs 11 at both ends of the body or barrel portion 10 of the spool. In view of the relatively short connecting webs 12, it will be noted that the exposed portions of ribs 11 (Fig. 2) will be substantially circular in cross-section.

Referring particularly to Fig. 3, a flange 15, which may be a flat plate or disc, or formed with a central hub 16, is provided with apertures 17 which serve to support the flange on the extending ribs 11, the apertures obviously being equal in number to the ribs 11. The length of the extending portions of ribs 11 is so selected in respect to the thickness of flange 15 to provide sufficient metal to head up the rivets as illustrated in Fig. 4, or form a countersunk head as illustrated in Fig. 5, the flange 15 in either one of the aforementioned heading operations illustrated in Figs. 4 and 5 being then secured to the body 10 of the spool, bobbin, pirn, or the like. Four internal ribs 11 have been illustrated as representing the preferred embodiment of the structure of the invention, although any suitable number of equally spaced ribs may be used. Also the internal ribs 11 have been illustrated as generally circular in

cross-section. Ribs of circular cross-section are preferred in that in this form they present cylindrical rivet shanks which lend themselves both to accurate fitting with respect to the apertures 17 in flange 15, as well as standardized button or countersunk heading tools and operations. Manifestly, any satisfactory number of ribs 11 may be employed, and the internal ribs could have a cross-section other than circular without departing from the scope and intent of this invention. In this connection, the amount of metal in the extending ribs 11 should preferably be just sufficient to fill out the selected rivet heads.

The flanged spool of this invention, which has been described hereinabove, permits the use of exceedingly thin metallic tubing, since the internal ribs 11 react to reinforce the wall of the spool body, which might otherwise be entirely too thin. The flange 15, in combination with the riveting operation for securing the same to the spool body, results in a sturdy spool assembly which withstands the vibrations experienced by such equipment at the high speeds of operation permissible with light weight spools. Also, the absence of seams, welded joints, and flange-connecting instrumentalities permits of a spool structure which will retain its dynamic balance over long periods of use. Magnesium, and its alloys, has been found exceedingly satisfactory, both in use in the textile industry as well as a source of extruded tubular spool bodies and forged or stamped flanges. Many other light metals and their alloys, however, fully meet the requirements for the production of equipment in accordance with the spool of this invention.

Although the invention has been described in terms of a particular spool construction, it is to be understood that the invention should not be limited thereto, since it will be manifest that the invention may be incorporated in other forms of textile equipment without in any way departing from the scope of this invention as defined in the appended claims.

What is claimed is:

1. A tubular spool comprising a tubular body portion having internal integrally formed ribs, a flange member, said ribs extending beyond the tubular body a sufficient distance to support and extend through said flange, said ribs being headed over to secure said flange to said tubular body.
2. A tubular spool comprising an extruded tubular body portion having internally formed integral ribs, a flange member, said ribs extending beyond the tubular body a sufficient distance to support and extend through said flange, said ribs being headed over to secure said flange to said tubular body.
3. A tubular spool comprising a tubular body portion having internal integrally formed ribs of substantially cylindrical cross-section, a flange member, said ribs extending beyond the tubular body a sufficient distance to support and extend through said flange, and said ribs being headed over to secure said flange to said tubular body.
4. A tubular spool structure comprising an extruded tubular body member having a relatively thin wall, equally spaced, internal, integrally formed ribs connected to the inner surface of said tubular body through the medium of short webs, said ribs being substantially heavier than the wall of the tubular body and extending beyond the ends of the body, flanges supported upon the extending portions of the ribs, said extending ribs being headed over to secure the flanges to said tubular body.
5. A spool comprising a plurality of flange members and a body member having internal integrally formed ribs extending throughout the length of the body member and projecting beyond the ends thereof, the projecting portion of each rib being of sufficient length to support and extend beyond a flange in abutment with each end of the body member, and said ribs being headed over to secure said flange members in rigid assembled relationship with the body member.

CHARLES BRAGLIO.

CERTIFICATE OF CORRECTION.

Patent No. 2,307,354.

January 5, 1943.

CHARLES BRAGLIO.

It is hereby certified that error appears in the printed specification of the above numbered patent requiring correction as follows: Page 2, second column, lines 9 and 10, claim 2, for the words "internally formed integral" read --internal integrally formed--; and that the said Letters Patent should be read with this correction therein that the same may conform to the record of the case in the Patent Office.

Signed and sealed this 9th day of March, A. D. 1943.

(Seal)

Henry Van Arsdale,
Acting Commissioner of Patents.
